[57] CLAIM

The ornamental design for a lizard shaped bottle opener, as shown and described.

DESCRIPTION

FIG. 1 is a top plan view of a lizard shaped bottle opener, showing my new design;

FIG. 2 is a left side elevation view thereof, the right side elevation view being a mirror image thereof;

FIG. 3 is a bottom plan view thereof;

FIG. 4 is a front elevational view thereof; and,

FIG. 5 is a rear elevational view thereof.
